UNITED STATES PATENT OFFICE.

NICHOLAS EDWARD CARROLL AND JAMES MULLINS, OF SANFORD, MAINE.

METHOD OF LASTING SHOES.

1,181,423.

Specification of Letters Patent.

Patented May 2, 1916.

Application filed March 7, 1911. Serial No. 612,817.

To all whom it may concern:

Be it known that we, NICHOLAS EDWARD CARROLL and JAMES MULLINS, of Sanford, in the county of York and State of Maine, have invented certain new and useful Improvements in Methods of Lasting Shoes, of which the following is a specification.

This invention relates to shoe-making and particularly to the step thereof known as lasting.

The invention is applicable to the purpose of lasting all boots and shoes, but has its particular use in connection with patent leather shoes. Much difficulty has been encountered in making shoes having uppers of this material, on account of the fact that it is extremely difficult to draw the upper smoothly about the toe of the last, without cracking the enamel or tearing or wrinkling the leather. As is well known, the enameled surface of patent leather is comparatively stiff and brittle, and is unable to yield so much as the leather itself when pulled. Consequently it very frequently happens that the enamel is broken and cracked when the leather is pulled around the toe of the last, or the leather or its enameled surface is otherwise marred. A large proportion of patent leather shoes are spoiled or injured in the making and require to be scoured and re-finished at those points mainly around the toe, where the leather has been sharply bent and pulled. Also especial care is necessary on the part of the lasters in order to avoid as far as possible injuries of this character.

Our invention is designed mainly to reduce the liability of injuring uppers, particularly those made of patent leather, in the manner indicated, and also to increase the capacity of the lasting machines and operators for turning out work. The invention consists in a method or mode of treating the partly completed shoes, and particularly the uppers thereof during the lasting operation.

In the following specification and claim we have described and claimed this method, in connection with a form of apparatus capable of being used to carry out the method, which is illustrated in the accompanying drawings.

In the drawings Figure 1 represents a perspective view of the apparatus. Fig. 2 is a front elevation of the same. Fig. 3 is a vertical section on line —3—3 of Fig. 2, and Fig. 4 is a horizontal section on line 4—4 of Fig. 2.

In practising our invention the upper is first placed upon the last and the heel is lasted. Then the upper is subjected to the step which constitutes the gist of our invention, and in the use of which the apparatus illustrated in the annexed drawing is employed. This step consists in making the upper leather, and particularly the enameled coating thereof soft, pliable and somewhat elastic or ductile by the application of moist heat. In performing this step the last with the upper thereon is so placed that the enameled coating of the leather is moistened and at the same time heated to such a degree as to soften the enamel, while the entire last and other parts thereon are also heated, but without being moistened to any great degree. At the conclusion of this step, and while the upper and last retain the heat given to them, the edge of the upper at the toe part thereof is drawn over the toe of the last in the manner usual in lasting shoes to complete the lasting operation.

An apparatus which may be employed in the practice of our invention consists of a box or case *a* inclosed on the back, ends, top and bottom, and partly on the front. A sufficient opening as shown at *b* is left in the front to admit the toe parts of lasts *c* having shoe uppers *d* thereon. The lower part of the front wall of the case consists preferably of a support *e* having places such as rounded notches *f* so made as to contain the instep of the last and support the same with the toe end projecting into the case.

In the bottom of the case is a pipe *g* which is designed to conduct steam thereunto, and is provided with perforations *h* within the case to permit escape of the steam. Preferably the bottom *a'* of the case is inclined downwardly toward the rear so that the deepest part thereof is at the rear, and the pipe is contained in said deepest part. The space above the pipe is filled with a packing of soft porous and absorbent material *i*, such material being conveniently cotton waste or anything else having the qualities mentioned. This material fills the bottom of the case to a height approximately such as shown in Fig. 3, so that a shoe placed in one of the notches *f* as shown in Fig. 3, will rest with the outer face of its upper in contact with the material. The moisture of the material then wets the outer surface of the upper leather, while the steam issuing from the pipe *g* and passing through the absorbent

material keeps the latter and the water held thereby at a high temperature, and also thoroughly heats the upper leather and the last. In the top of the case is an outlet *j* 5 through which the uncondensed steam and the vapors of oils and dressings evaporated from the leather pass away. In the bottom of the case is a drain *k* which permits the surplus water of condensation to escape. 10 Such of the steam as condenses on the top of the case runs down toward the front wall, because the top is inclined downwardly toward the front. The water collected on the front wall is prevented from dripping upon 15 the last, and the parts of the shoe thereon, by a gutter *l* extending across the lower edge of the front wall above the opening *d*. The gutter catches the drip and conducts it to the sides of the casing, where it falls 20 without wetting the lasts, the insole or the inner side of the upper.

In the practice of our invention the uppers are first placed on the lasts, to which also the inner soles are attached in the usual 25 manner, and the upper is pulled over, its edges being fastened to the bottom of the last at a few points to hold it preliminarily to the final and complete operation of lasting. Then the last is placed in one of the 30 notches *f* in the support *e*, in an inverted position with the outer face of the leather at the fore part of the shoe resting on the wet absorbent material. We find that it is convenient to have three or four places for the 35 shoes and lasts in the heater, and to keep these places filled, the operator or his helper placing a fresh last with its upper in one of the notches as soon as a heated last with its upper is removed for the lasting operation. The heated lasts are taken from the 40 heater in the order of their admission thereto and thus each partly completed shoe is subjected to heating during the time taken to last three or four shoes. This time is sufficient for thoroughly heating the upper 45 leather, heating the last and moistening the enameled surface of the upper leather.

As a result of the heating and moistening to which the enameled surface of the upper 50 is subjected, it is made softer and more pli-

able, so that it can be bent about the abrupt edges of the last at its bottom and pulled around the toe tightly enough to finish the toe smoothly without cracking or breaking. Thus the improvement in the process of lasting shoes which we have invented enables better work to be done and diminishes the proportion of injured and spoiled shoes. 55

We have also found that by use of our invention the capacity of both lasting machines and operatives to accomplish work is increased, and that also fewer lasts need be employed at shoe factories for making the standard output of shoes, than heretofore. This is partly due to the fact that because 60 the entire upper and last are heated, the shoe dries more rapidly and the last may be withdrawn from the completed shoe at an earlier point of time in the shoe-making operation than heretofore, thus shortening the 65 length of time that each last must be in use in any one shoe, and enabling the lasts to do more service. The time of the operatives is saved partly as a result of the lessened difficulty of drawing the upper about the toe, 70 and the lessened need of taking pains to avoid injuring or spoiling the upper. 75

We claim—

The improvement in the manufacture of patent leather shoes which consists in placing a partly lasted upper with the last therein and before the upper has been shaped about the toe of the last, so that the toe part projects into an inclosed space, with the enameled surface of the upper leather in contact with a mass of moist fibrous material, injecting steam into such mass of material for a sufficient length of time to heat the leather and last and thereby soften the enameled surface of the leather, and finally removing the upper and last and fitting the heated, moistened, and softened toe of the upper about the toe of the last. 85

In testimony whereof we have affixed our signatures, in presence of two witnesses.

NICHOLAS EDWARD CARROLL.

JAMES MULLINS.
